UNITED STATES PATENT OFFICE

127,917

DESIGN FOR A CRIBBAGE BOARD

Calvin D. Williams, Cloquet, Minn., assignor of one-half to Abner H. Nerhaugen, Duluth, Minn.

Application February 14, 1941, Serial No. 99,005

Term of patent 14 years

To all whom it may concern:

Be it known that I, Calvin D. Williams, a citizen of the United States, residing at Cloquet, in the county of Carlton and State of Minnesota, have invented a new, original, and ornamental Design for a Cribbage Board, of which the following is a specification, reference being had to the accompanying drawing, forming part thereof.

In the drawing:

I claim:

The ornamental design for a cribbage board, as shown.

CALVIN D. WILLIAMS.
